9 Claims. (Cl. 225—1)

1

This invention relates to apparatus for dispensing beer on draught by subjecting the beer in the cask to the pressure of a mixture of carbon dioxide and air. The object of the invention is to provide an improved apparatus for this purpose.

According to the present invention the apparatus comprises a supply of carbon dioxide, a compressor (similar to those used for delivering beer by compressed air), a reservoir for the mixture of CO₂ and air, pressure-responsive means for automatically controlling the compressor in accordance with the pressure of the mixture in the reservoir, and a valve regulating the supply of carbon dioxide to the reservoir also controlled by the pressure-responsive means. The proportion of CO₂ to air is between 1 to 3 and 1 to 10 by volume.

When the pressure in the reservoir falls below a certain value, for example, below 20 pounds per square inch, the pressure-responsive device closes electric contacts and starts up the compressor, and when the pressure rises above a higher predetermined value, for example 50 pounds per square inch, it opens the contacts and shuts off the compressor.

A supply of carbon dioxide under pressure is provided, for example in a steel bottle, from which bottle the carbon dioxide issues through a pressure-reducing valve and an electrically-operated cut-off valve into a mixing nozzle. The mixing nozzle is directed into a pipe, which may be formed similarly to the choke tube of a carburetor and which leads to the intake of the compressor so that carbon dioxide, issuing from the nozzle is thoroughly mixed with the air being drawn into the compressor. The electrically-controlled cut-off valve for the carbon dioxide is connected to the electric supply to the compressor so that whenever the pressure-responsive device switches on the compressor it simultaneously opens the carbon dioxide valve and vice versa.

The rate at which carbon dioxide will issue from the mixing nozzle will depend on the pressure at which it is supplied thereto, and this is determined by the pressure-reducing valve. The latter is adjustable so that the pressure on its delivery side can be varied, thus varying the rate of flow of carbon dioxide, and hence the proportion of carbon dioxide in the mixture. It may be that as the pressure in the mixture reservoir rises, the rate at which the compressor draws in air will vary slightly but even if the mixture is initially slightly weaker in carbon di-

2

oxide and towards the end slightly richer, the apparatus may be adjusted so that as a whole the proportions of the charge pumped in are within the desired limits. The delivery pipe from the compressor into the mixture reservoir may, moreover, be arranged so as to stir up the contents of the reservoir and ensure thorough mixture of the carbon dioxide and air.

A diagrammatic arrangement of an apparatus according to the present invention is illustrated by way of example in the accompanying drawing in which a pressure-controlled compressor A, driven by an electric motor B, communicates with a reservoir C containing a mixture of compressed air and carbon dioxide. The carbon dioxide is supplied under pressure from a steel bottle D and issues through a pressure reducing valve D¹ and an electrically operated cut-off valve E into a mixing nozzle F. The mixing nozzle is directed into a pipe F¹ in form similar to the choke tube of a carburetor, and this pipe leads to the intake of the compressor A so that carbon dioxide issuing from the nozzle F is thoroughly mixed with the air before being drawn into the compressor. The electrically-operated cut-off valve E is connected to the electric supply to the motor of the compressor and is controlled by a pressure-responsive device G with which the reservoir communicates.

The arrangement is such that when the mixture of carbon dioxide and air in the reservoir C falls below a certain value, say twenty pounds per square inch, the pressure-responsive device G closes the contacts G¹ and so starts up the compressor motor B simultaneously opening the valve E. Similarly the valve E closes and the motor is cut out when the pressure in the reservoir C reaches some higher predetermined value, for example fifty pounds per square inch.

The rate at which carbon dioxide will issue from the mixing nozzle F will depend on the pressure at which it is supplied thereto, and this in turn is determined by the pressure-reducing valve D¹ which is preferably adjustable. Hence the pressure on the delivery side of the valve D¹ can be varied and the rate of flow of the carbon dioxide and consequently the proportion of carbon dioxide in the mixture can be adjusted. The rate at which the compressor draws in air will vary slightly as the pressure in the mixture reservoir C rises, but if the mixture is initially weaker in carbon dioxide, adjustments may be made so that, as a whole, the proportions of the charge pumped into the reservoir are within the desired limits. To ensure that the contents

of the reservoir are well mixed, the delivery pipe A¹ from the compressor is extended into the reservoir in the form of an inclined nozzle A² as shown in the diagram.

The apparatus above described is preferably employed in conjunction with the arrangement set forth in British Patent Specification No. 499,743, in which a number of casks are provided with a gas reservoir and a gas manifold connecting together the upper parts of the casks and also connecting them to the bottom of the reservoir so that beer can issue into the reservoir from casks of beer which are conditioning and can be driven back into a cask by supplying compressed air to the top of the reservoir as beer is delivered from that cask.

In applying the present invention to such an arrangement, the reservoir C for the mixture of carbon dioxide and air is connected through a reducing valve C¹ to the top of three beer gas reservoirs H, J and K, each having a non-return valve H¹, J¹, K¹ and respectively connected to a set of casks H², J², K². Each set of casks is connected to a separate draw-off pipe having a tap and outlet faucet H³, J³, K³. Suitable stop-cocks are provided between the various casks, the beer gas reservoirs and the draw-off pipes.

The invention is of particular value where trade is rapid or where the beer contains but little natural gas, as in the case of rack beer or lager beer, the beer gas pressure must be supplemented to a considerable extent, and in this case the present invention offers substantial advantages even as compared with that of the prior specification.

It will be appreciated that the invention is not limited to the specific arrangement described. Thus the carbon dioxide may be mixed with the air on the delivery side of the compressor with a view to avoiding waste of power in compressing the carbon dioxide. On the other hand, the arrangement already described with reference to the drawing has the advantage that the bottle of carbon dioxide can be more completely emptied, since the pressure in it can be allowed to fall to atmospheric pressure.

Having now particularly described and ascertained the nature of my said invention and in what manner the same is to be performed;

What is claimed is:

1. Apparatus for dispensing beer on draught, comprising a supply of carbon dioxide, a compressor, a reservoir for a mixture of carbon dioxide and air, pressure-responsive means for automatically controlling the compressor in accordance with the pressure of the mixture in the reservoir for maintaining said pressure between selected pressure limits, a valve regulating the pressure of the supply of carbon dioxide to the reservoir, a cut-off valve interposed between said regulating valve and the reservoir also controlled by said pressure-responsive means and a reducing valve for delivering the mixture of carbon dioxide and air at constant pressure from said reservoir.

2. Apparatus for dispensing beer on draught, comprising a supply of carbon dioxide, a pressure regulator therefor, an electrically-operated compressor, a reservoir into which a mixture of air and carbon dioxide is delivered by the compressor, a reducing valve for delivery of the mixture at constant pressure from the reservoir, a pressure-responsive device communicating with the reservoir, a cut-off valve in the pipe connecting

the pressure adjusted supply of carbon dioxide to the reservoir controlled by the pressure-responsive device, and a switch for the compressor motor also controlled by said pressure-responsive device whereby the carbon dioxide and air are proportioned in predetermined relation for entry into the reservoir.

3. Apparatus for dispensing beer on draught as claimed in claim 2, wherein the carbon dioxide is mixed with the air on the intake side of the compressor.

4. Apparatus for dispensing beer on draught as claimed in claim 2, in which the reservoir is connected to a plurality of casks each connected to a beer gas reservoir and leading to an outlet faucet.

5. Apparatus for dispensing beer on draught as claimed in claim 1, in which the mixture of air and carbon dioxide is so discharged through a nozzle within the reservoir that the contents of the latter are stirred up.

6. Apparatus for dispensing beer on draught as claimed in claim 1 in which the proportion of carbon dioxide to air is between 1 to 3 and 1 to 10 by volume.

7. Apparatus of the class described comprising a beverage container having a draught tap connected thereto, a pressure fluid reservoir adapted for connection with said container, a pressure regulator for delivering the fluid at constant pressure from the reservoir to said container, an electrically operated air pump, an electric control switch for said pump and responsive to selected pressures in the reservoir, a mixing valve connected to the intake of the air pump, a carbon dioxide supply means, a pressure regulating valve for said supply means, a tube leading from said valve, an electric valve in said tube between said regulating and mixing valves, and circuit means connecting with the electrically operating valve and said control switch for simultaneously actuating said valve and said pump whereby the reservoir is maintained constantly charged with a mixture of air and carbon dioxide of approximately predetermined portions and at pressures within predetermined pressure ranges.

8. In an apparatus for dispensing draught beer from the keg in unchanged condition over an extended period of time the combination of a pressure reservoir adapted for connection and constant communication with the keg, an electrically operated air compressor, means responsive to the pressure in the reservoir for controlling the compressor and automatically maintaining a predetermined range of dispensing pressure in the reservoir, a source of carbon dioxide, a regulator valve therefor, a tube leading from the regulator valve, an electrically controlled valve for the tube, a mixing valve connected to the air intake of the compressor, said tube entering the mixing valve and delivering an adjusted proportioned amount of carbon dioxide to the intake air during operation of the compressor, an electrical circuit to the electrically controlled valve energized and deenergized simultaneously with the air compressor under the control of the pressure responsive means whereby the proportions of air and carbon dioxide delivered to the reservoir and keg are maintained at a constant and a pressure regulator between the reservoir and the keg for maintaining a constant selected pressure of said proportioned mixture of air and carbon dioxide on the beer in the keg.

9. In combination a supply of carbon dioxide, an electrically operated compressor, a reservoir

into which a mixture of air and carbon dioxide is delivered by the compressor, and output pressure regulator in the reservoir for delivering the mixture at a constant selected pressure, a mixing valve for the intake air of the compressor and said carbon dioxide, means for regulating the supply of carbon dioxide to the mixing valve for predetermining the proportion of carbon dioxide in relation to the air intake, pressure responsive means communicating with the reservoir, a valve controlling the supply of carbon dioxide to the mixing valve, and controlled by said pressure responsive means, and a switch for the compressor controlled simultaneously by said pressure responsive means.
